Robert W. Blee and Renor S. Faidy, Jefferson County, Ky., assignors to General Electric Company, a corporation of New York

Filed Nov. 29, 1961, Ser. No. 67,746

Term of patent 14 years

(Cl. D81—4)

FIG.2

FIGURE 1 is a front perspective view of a cooking oven or similar article embodying our new design;

FIGURE 2 is a fragmentary cross-sectional elevational view taken on the lines 2—2 of FIGURE 1.

The upper and lower panels shown on the front of the oven in FIGURE 1 are shaded to illustrate contrast.

The dominant features of this design reside in the portions shown by the solid lines.

The side of the oven not shown is substantially like the side shown, and the back panel is flat and substantially plain.

We claim:

The ornamental design for a cooking oven or similar article, as shown and described.
